HOUSING FOR A CARPET SWEEPER

Howard A. Anderson, Pittsburgh, Pa., assignor to Bissell
Inc., Grand Rapids, Mich., a corporation of Michigan

Filed Sept. 21, 1962, Ser. No. 71,808

Term of patent 14 years

(Cl. D9—2)

Zig-1

Zig-2

Zig-3

FIGURE 1 is a front perspective view;
FIGURE 2 is a top plan view; and
FIGURE 3 is an end elevational view of a housing for
a carpet sweeper embodying my new design.
The side and end not shown are substantially like the
respective side and end shown.

I claim:

The ornamental design for a housing for a carpet
sweeper, as shown and described.
